UNITED STATES PATENT OFFICE.

HENRY GOLDWATER, OF NEW YORK, N. Y., ASSIGNOR TO JAMES TYROLER,
OF SAME PLACE.

APPARATUS FOR REFINING ILLUMINATING AND LUBRICATING OILS.

SPECIFICATION forming part of Letters Patent No. 366,720, dated July 19, 1887.

Application filed May 6, 1886. Serial No. 201,344. (No model.)

To all whom it may concern:

Be it known that I, HENRY GOLDWATER, of the city and county of New York, in the State of New York, have invented a certain new and 5 useful Improvement in Apparatus for Refining Illuminating and Lubricating Oils from Crude Petroleum, of which the following is a specification.

Letters Patent issued to me February 2, 1886, No. 325,281, set forth an apparatus in which certain novel provisions are made for arresting and returning unevaporated particles which are carried up with the light vapor. Such are usually of a denser or less volatile grade of oil; 10 but the oil thus arrested and returned differs in important points from the mass which remains in the retort. I have devised apparatus by which the mixing of the particles thus arrested with the mass of crude material in the 15 retort is avoided.

I conduct the arrested particles into one or more smaller vessels or retorts arranged near the main retort and favorably conditioned to receive a gentle heat by which the contents 20 may be evaporated. The volatile portion is led away to a condenser. The denser portion of the separated product thus treated is drawn off either continuously or at intervals. Instead of a series of traps divided by a considerable space, as shown in my former patent, I 25 employ a single vessel of considerable height tapered from the lower end upward, so as to present favorable surfaces over which water may flow. A single reservoir at the top receives water, which is allowed to flow in a thin 30 sheet, or any other convenient form, down the exterior of the vessel. It is arrested in an annular chamber provided around the bottom and led away. The vapors in rising through 35 this vessel are passed successively through contracted apertures in a succession of horizontal plates or platforms. The arrested particles are allowed to return from stage to stage within this single chamber, and the vapor, 40 becoming more and more perfectly separated from the unevaporated material, is discharged from the top, the conditions being similar to my former apparatus in the fact of the same water being used as a cooling medium 45 at all the stages, the rising vapor meeting the water at first in its warmest conditions and at

the successive stages encountering it at a lower temperature.

It has been found of advantage to introduce the vapor of water—steam—to mingle with the 55 hydrocarbon vapors and liquids to be afterward separated from the refined product. I employ means for effecting this at several stages in the progress of my vapors.

My improved apparatus is intended to separate more completely petroleum and analogous oils into the desired grades with a more than usual degree of perfection, and to treat large 60 quantities continuously and rapidly.

The accompanying drawings form a part of 65 this specification, and represent what I consider the best means of carrying out the invention.

Figure 1 is a longitudinal section; Fig. 2, a transverse section. Fig. 3 is a horizontal section on the line *y* *y* in Fig. 1, on a larger scale; 70 and Fig. 4 is a cross-section on a larger scale. This figure corresponds to Fig. 3, but with some of the parts omitted.

Similar letters of reference indicate corresponding parts in all the figures. 75

A is the main retort, set in masonry, and exposed to the heat of a furnace below. It will be understood that any ordinary or suitable means are employed for regulating the 80 heat applied to this and to the other portions of the apparatus which are exposed to the action of the fire.

B are pipes of liberal size, leading upward and obliquely toward each other from two 85 points in the upper portion of the retort. They deliver the vapor with the material carried therewith into the upper portion of a chamber, *E*, in which the first part of the separation of the unevaporated particles is 90 effected. The end of each is equipped with a broad plate, *B'*, which extends upward and downward, and aids to arrest circulation and induce a quiescent condition of the vapor after its delivery in the chamber against a hollow 95 partition, *F*, which extends across the upper portion of the interior of chamber *E*. This hollow partition *F* performs four important functions: first, of mechanically arresting all unevaporated material, the particles being 100 projected against it by their momentum, and adhering to it and trickling down; second,

arresting and limiting the vigor of the circulation of the vapor, so as to induce the quiescent condition which is favorable to the complete separation of the unevaporated particles; 5 third, cooling the vapor projected against it, and thereby condensing the most volatile portion; and, fourth, forming within the partition F a chamber in which an exactly uniform temperature is maintained by the constant impact of the hot vapor on the exterior, in which 10 chamber the unevaporated liquid descending from above may find a liberal supply of heat to insure the evaporation and rise of the portions which are sufficiently volatile to evaporate at that temperature, while those portions 15 which are not sufficiently volatile descend and drop from the lower edge. This action is due to the fact that the vapors fresh from the retort which rise through the pipes B and are 20 projected in two strong currents against the hollow partition F are hotter than the vapors which have traversed the chambers above, and are especially hotter than the material descending through F. My arrangement 25 insures a just sufficient addition of moderate heat to F to enable it to re-evaporate the volatile elements in its contents without re-evaporating the denser elements.

The unevaporated portions, either separated 30 from the vapor in its first reception into E or returned into it through the hollow partition F, collect in the bottom of E. Instead of transmitting them from thence back into the main retort or still A, to mingle with the 35 crude material there contained, I lead them down through pipes G, one at each side, which communicate, respectively, with side chambers or sub-retorts, H, arranged within the same furnace, and exposed to the desired amount of 40 heat. In this they are redistilled, the volatile portions rising through a pipe, I, and flowing away to a condenser, which may be of any ordinary or suitable construction, in which 45 they are reduced to a liquid form, and either with or without further treatment subsequently barreled or otherwise stored.

J are pipes controlled by valves j. Through these the unevaporated material is drawn from the sub-retorts H either constantly or at intervals. 50 This may be subsequently treated in the main still A, or other suitable apparatus, to further separate its constituents, if desired.

K are pipes leading from the sub-retorts into the upper portion of the main still A. These 55 are controlled by valves k, and may be opened at intervals to afford a free communication between these parts when desired. The volatile products from these side chambers or sub-retorts procured by condensing the vapor 60 rising through the pipe I are illuminating-oils of great density and high illuminating powers, corresponding to what is generally known in the trade as "signal-oil." The vapors which rise through the chamber E and 65 are treated in the upper portions of the apparatus are of a lighter and more volatile character. They produce the kerosenes, naphthas,

and other light oils. The separations to which these materials are subjected may be more or less extended. I will represent apparatus for 70 separating once before the vapors rise into what I term the "bell," corresponding to the series of traps in the former apparatus.

L are pipes of suitable capacity leading from the two chambers into which the casing E is almost completely divided by the hollow partition F. The vapor rising through these is discharged into the upper portion of a casing, M, being discharged against a central partition, N, therein, which extends from the top 80 downward nearly but not quite to the bottom. This partition need not be hollow. It does not serve as a means for leading down unevaporated material; but it performs an important function in presenting a suitable surface to arrest the particles of liquid which still remain mechanically suspended or otherwise carried along in the vapor. It also aids to check the motion of the vapor and reduce it to the quiescent condition which is desirable 90 for the further separation of the unevaporated parts. All the liquid material here arrested, as also that which trickles down from the apparatus above, to be presently described, is led down through the hollow partition F into 95 the base of E, and is led into the side chambers, as before described. The vapor, now pretty effectually separated from particles of unevaporated liquid, rises through the two pipes O and joins into one, P. There are 100 some conditions under which this vapor may be condensed and stored without further treatment. When this is desired, I close the valve p and open a valve, q, controlling a pipe, Q, which extends laterally from this part of the apparatus to a suitable condenser. 105

Steam is received from a boiler (not represented) through a pipe, S, which is branched as follows: Two branches, S', lead to the corresponding side chambers, H. When the cocks s', controlling these branches, are open, steam is admitted in any desired quantities therein. Another branch, S", controlled by a cock, s", leads the steam into the base of the casing E. Another branch, controlled by a cock, s", leads 115 steam into the pipe S'. This should only be used when the cock q is open. When, as may usually be preferred, the vapor is to be further treated to separate the denser and discharge only the lighter portions, the valve q 120 is kept closed and the valve p open. Under these conditions the vapor rises from P into the bell W, where it passes a series of horizontal partitions, Y. The vapor traverses successively through short pipes Y', extending 125 upward from each. The liquid condensed in the bell at the several stages gathers on the upper surfaces of these partitions, and descends through pipes Y", which extend a little distance downward from the several partitions. The liquid thus obtained gathers in 130 the bottom of the bell, and may, if desired, be led away through a pipe (not represented) to be stored or further treated. I prefer, for

general purposes, to return this liquid and mingle it with the particles mechanically separated below. All will be properly separated in the side chambers, H.

- 5 The condensation in the bell is effected by water presented to the exterior. The upper edge of the bell has a rim, W', into which water flows through a pipe, U, controlled by a cock, u. The upper edge of this rim should be 10 maintained exactly level, so that the water will flow over uniformly and trickle down on the exterior. Provisions may be made, if desired, for compelling this water to traverse spirally. It bathes the exterior of the bell.
- 15 On its first introduction into the reservoir on the top of the bell its temperature is low. In its moving in a thin sheet over the exterior of the bell it becomes raised in temperature; but it is still capable of effecting some condensing 20 of the volatile vapors in the lower portion of the bell. The whole surface is effective for condensation.

W' is a lip or rim encompassing the bottom of the bell.

- 25 X is a pipe which leads away the water arrested thereby, and conveys it to a tank or drain. (Not represented.)

The unevaporated vapors rising from the bell flow through a pipe, Z, to a condenser. 30 The product is more uniformly conditioned by reason of its having been subjected to successively cooler surfaces in the bell, and having correspondingly parted by fractional distillation with its most easily condensable portions.

- 35 One advantage due to my combination and arrangement of the apparatus is, that I get a larger proportion of dense oil and get it more completely separated both from the lighter elements and from the denser—the paraffine 40 and tar. This is due largely to the action in my side chambers or sub-retorts, H, and the passages connecting these with the other parts; but it is also due in part to the favorable conditions for separating in the hollow partition F.

- 45 I am aware of the patent to A. Millochau, No. 53,167, dated March 13, 1866, for condensing a portion of the vapor from an outer still and carrying the liquid thereby obtained into an inner still to be further treated; and also of 50 the patent to T. McGowan, dated May 16, 1882, No. 257,961, in which condensed portions are returned first to a retort outside and afterward transferred to the main retort. I do not claim, broadly, the returning of condensed products 55 to a different chamber from the first or main retort.

Modifications may be made in the forms and proportions of the apparatus without departing from the principle or sacrificing the advantages of the invention.

- I can duplicate or triplicate or otherwise increase the extent of the surfaces and the volume of the chambers or casings. Provisions may be made for separately taking away the 65 liquids gathered on the several horizontal partitions Y in the bell.

I can dispense with the provisions for intro-

ducing steam at some of the points represented. I attach importance to the introduction of steam at the several stages for its well-known 70 effect in softening the action. The steam-pipes constitute in their combination with my apparatus a means of applying and diffusing heat and hastening away the vapors to expedite the action of the apparatus.

I can use the apparatus successfully with only one of the side chambers, H. It may be made larger than is here shown. I can employ a separate fire for heating it instead of, as shown, exposing it in the same furnace as the main 80 retort. I can provide screens or other devices for varying the relative temperatures of the retorts. I propose under some circumstances to inclose a chamber corresponding to the sub-retort H in the interior of the main retort A, 85 providing the connections, as here shown, for leading away the vaporized portion and draining off the unevaporated either constantly or at intervals. Such an arrangement offers advantages in the uniformity of the heat which 90 it would receive, being transmitted through the medium of the general contents of the main retort; but, on the other hand, the sub-retort exposed to direct heat outside can act more efficiently. I prefer the arrangement shown. 95 I propose under some circumstances to employ two or more of the chambers E, with their hollow partitions F mounted one above another.

In such case the drippings from the uppermost will descend, protected by the sides of the partition from any disturbance, through the chamber below, and thus be transmitted from one to another, as many as may be desired. In each the descending liquid will be inclosed within walls of a slightly higher temperature 100 under conditions eminently favorable to a delicate separation, the parts which are more volatile separating and rising, while the parts which are less volatile continue their descent.

It will be understood that any ordinary or suitable provisions may be employed for graduating the heat in the furnace and for attaining all the ordinary adjustments. The introduction of the crude material and the discharge of the unevaporated portions from the main retort may be conducted in the ordinary manner.

I claim as my invention—

1. In a distilling apparatus, the combination of the main retort A, sub-retorts H, a suitable furnace for heating the same, the chamber E, seated thereon, a pipe connecting the bottom of the chamber E with the sub-retort, and pipes for leading off the vapors from the retort and sub-retort, substantially as described.

2. In a distilling apparatus, the combination of the main retort A, sub-retorts H, and means for heating the same, the pipes K, connecting the sub-retorts with the main retort, suitable controlling means, as the valves k, for said pipes, the chamber E, the pipes B, connecting this chamber with the main retort, and pipes G, connecting said chamber with the sub-retorts, all arranged to operate as herein specified.

3. In a distilling apparatus, the combination of the retort A, means for heating the same, chamber E, seated thereon, pipes B B, connecting the retort A and the chamber E, and partition-plates B' B', extending from the top and across said chamber nearly to the bottom thereof, forming three chambers therein and receiving the pipes B B, the return-passage, the chamber M above the chamber E and connected therewith by means of the vapor-pipes L L, and partition N, extending from the top of said chamber across the same and nearly to the bottom, all substantially as described.

4. In a distilling apparatus, the combina-

tion of the retort A, sub-retorts H, and chamber E, connected as described, and means for heating the same, the steam-pipe S, with branches connecting the same to the pipe Q, sub-retorts H, and chamber E, respectively, substantially as herein specified.

In testimony whereof I have hereunto set my hand, at New York city, this 3d day of May, 1886, in the presence of two subscribing witnesses.

HENRY GOLDWATER.
